CABINET CONSTRUCTION

Gregg F. Forsthoefel, Adrian, Mich., assignor to Westinghouse Electric & Manufacturing Company, East Pittsburgh, Pa., a corporation of Pennsylvania

Original application January 19, 1933, Serial No. 652,562. Divided and this application May 26, 1939, Serial No. 275,832

8 Claims. (Cl. 220—9)

This application is a division of my copending application Serial No. 652,562, filed January 19, 1933.

My invention relates to cabinets for refrigerators and the like, more particularly to a double-wall heat-insulated cabinet, and it has for an object to provide an improved cabinet construction.

A further object is to provide an improved means for mounting the breaker strips which extend between the edges of the inner and outer wall members at the door opening to close the space between said wall members.

A particular object is to provide means for mounting the breaker strips more quickly, in order to reduce the cost of manufacture.

A further object is to provide a cabinet body which may be manufactured at low cost.

A further object is to provide an improved refrigerator door construction.

In accordance with my invention, I provide a breaker strip having a groove at one lateral edge engaging the edge of the inner wall of the cabinet. Spring means are provided for retaining the other edge of the breaker strip against a flange at the adjacent edge of the outer wall and for yieldingly maintaining the groove in engagement with the edge of the inner wall.

In accordance with a further feature of my invention, the outer sheet metal casing of the cabinet comprises one sheet forming the front wall and the adjacent marginal portions of the side walls, and a separate sheet or sheets forming the remaining portions of the side walls and the rear wall. The adjoining edges of the side wall portions have inwardly-extending flanges clamped together by spring clips.

The above and other objects are effected by my invention as will be apparent from the following description and claims taken in connection with the accompanying drawings forming a part of this application in which:

Fig. 1 is a perspective view of the cabinet as it appears before the door and top are assembled thereon;

Fig. 2 is a horizontal sectional view of the left hand side of the cabinet with the door in closed position, taken on the line II—II of Fig. 5, the right hand side being symmetrically similar in all respects material to the present invention;

Fig. 3 is an elevational view showing the rear side of the breaker strip as it appears from the line III—III of Fig. 2;

Fig. 4 is a fragmentary plan view showing a corner of the door when partially assembled; and,

Fig. 5 is a vertical sectional view of the cabinet, taken along the line V—V of Fig. 2.

Referring to the drawings more in detail, I show, in Fig. 1, a cabinet 10 having a food compartment 8 and a compartment 9 for the refrigerating unit (not shown), the latter compartment being shown in this case above the food compartment. The cabinet 10 comprises an outer casing 11 and a one-piece inner casing or liner 12 for the food compartment, both casings being preferably made of sheet metal. The inner surface of the liner is preferably provided with a finish of porcelain enamel, while the exterior of the outer casing is finished in any suitable way, as by lacquer. The respective walls of the casings are disposed in spaced relation, and the intervening space is filled with suitable heat-insulating material. In the present embodiment, the heat-insulating material includes, as shown in Fig. 2, package insulation 13, loose fibrous insulation 14, and preferably relatively rigid insulating material, such as "Celotex" or cork board, between the rear walls of the casings.

The outer casing 11 includes a single sheet member 16 forming the front wall, with a door opening 17 formed therein having turned flanges 33 at its edges, and also forming the adjacent vertical marginal portions 18 of the side walls. Sheet members 19 form the remaining portions of the respective sides, said members having flanges 22 at their rear edges, to which a rear wall 24 is suitably attached, as by screws 23. The adjacent edges of the side wall portions 18 and 19 of each side wall are formed with flanges 25 and 26, respectively, extending inwardly in side-by-side relation. The flange 26 is continued to form a forwardly-extending portion 27. The flanges 25 and 26 are clamped together by means of a spring clip or clamp ring construction 28. The clip 28 may be, as shown, continuous from top to bottom of the cabinet. The flanges 27 bear against the edges of the flanges 25 to retain the side wall portions 18 against outward movement, the flanges 25 being part of the single sheet member 16, so that separating movement of the side wall portions 18 is prevented. The side wall portions are retained against inward movement toward each other by the heat insulation 13, and the liner 12, thereby retaining the side wall portions 18 in alignment with the side wall portion 16.

The outer casing 11 further includes a top wall member 29 and a bottom wall member 31, each of which has a flange 32 at the rear edge secured to the rear wall 24 by screws. The forward edges of the top and bottom wall members

28 and 31 are connected by screws to supporting members 33' and 34, which are connected by spot welding to the flanges 33 at the upper and lower edges of the door opening 17. The spot welding on the upper flange 33 is above the line of vision, while that on the lower flange 33 is partly covered by the lower breaker strip and is relatively inconspicuous for the reason that the visible portion of the flange is narrow. Metal 10 finishing to remove the welding spots is, therefore, not necessary. The supports 33' and 34 are formed to fit against the front wall and the flanges 33, as shown on the drawings, and by making these supports separate from the members 29 and 31, smaller blanks, which are more suitable to the forming or blanking operation, may be used. By the use of the supporting members 33' and 34, the dimensions of the top and bottom wall members 29 and 31 are reduced to 15 the extent that one of these wall members may be formed of the sheet metal cut out from the sheet member 16 in forming the door opening 17. In the present embodiment, the top wall member 29 is thus formed.

20 The top wall of the food compartment is formed with an opening 35 for the insertion of the evaporator from the top into the food compartment. The adjacent edges of the casings are connected by a breaker strip 36, of any suitable 25 material of low heat conductivity, such as stainless steel or rubber.

The liner 12 is anchored to the outer casing 11 by means of bolts 37 and insulating tubular spacers 38 extending between the rear walls of 35 the casings. Fiber washers 39 are preferably disposed under the heads of the bolts 37 to break the heat path between the casings through the bolts.

The liner 12 is provided with an opening in 40 the front side registering with the opening 17 of the outer casing. In the present embodiment, the entire front side of the liner is open, the forward edges of the top, bottom, and side walls of the liner extending forwardly toward the inwardly-extending flanges 33, which are formed along the edges of the door opening 17.

Breaker strips 41, extending between the flanges 33 and the adjacent edges of the liner 12 are provided to close the space between the 50 casings around the door opening. In accordance with the present invention, the breaker strips are of improved construction, enabling mounting thereof in the cabinet in a shorter period of time. They are made of any suitable material having 55 low heat conductivity, for example, wood, resinous condensation product, etc. Each breaker strip is formed with a groove 42 at one lateral edge, into which the adjacent edge of the liner 12 is inserted. The other lateral edge of the 60 breaker strip bears against the outer side of the adjacent flange 33. As shown in Figs. 2 and 3, spring members 43 are attached to the back side of the breaker strip and bear against the inner surface of the flange 33 to retain the adjacent 65 edge of the breaker strip against the flange. Spring members 44 are also attached to the back side of the breaker strip and bear against the inner surface of the front wall, for the purpose of biasing the breaker strip toward the rear of 70 the cabinet, which is longitudinally of the cross-section of the breaker strip, in order to retain the grooved edge of the breaker strip in engagement with the adjacent edge of the liner.

The breaker strips 41 are attached after the 75 inner and outer casings are assembled into a

unit. The spring members 43 and 44 are first engaged under the flange 33, and the breaker strip is then brought forward, the spring members 44 being deflected away from the flange 33. The rear edge of the breaker strip is moved transversely into alignment with the adjacent edge of the liner. The breaker strip is then moved rearwardly until the liner edge engages the bottom of the groove 42, allowing the springs 44 to move toward the flange 33. The breaker strip now occupies the position shown in the drawings, particularly Fig. 2, and serves as a seat or stop for the door of the cabinet. The forward edge of the breaker strip is retained against the flange 33 by the springs 43, which bias the forward edge transversely of the breaker strip, while the springs 44 bias the strip longitudinally of its cross section to engage the groove 42 with the adjacent edge of the liner.

The cabinet is provided, as shown in Fig. 2, 20 with a door 45 fitting in the door opening 17, said door having an outer wall 46 and an inner wall 47, both preferably of sheet metal. The inner wall is provided with forwardly-extending flanges 48 which close the space between the inner and outer walls. The marginal portions of the outer wall 46 are first bent toward the inner side of the door as shown at 48' and then bent reversely as shown at 49, to provide a flange for the door. Angle pieces having two sides 50 and 51 are 25 provided, the sides 50 being inserted under the reversely bent portions 49 and retained therein by driving in filler pieces 52 under the sides 50. At the corners of the door, the ends of the sides 50 of the angle pieces overlap and are secured to 30 each other and to the reversely bent portion 49, as by screws 53, shown in Fig. 4. The outer wall is laid on its front face and package insulation 54 and loose fibrous insulation 55 is placed thereon as shown in Fig. 2. A rubber gasket 56 is 40 placed on the reversely bent portion and the angle pieces, and then the inner wall is brought down on the assembly and secured thereto by screws 57 extending through the flanges 48 and the sides 51 of the angle pieces, which are spaced 45 by the gasket 56 to provide minimum heat path between the inner and outer walls.

From the above description, it will be seen that I have provided a cabinet, the parts of which comprise relatively small and simple stampings, thereby enabling rapid punch press operation and making for ease of handling, and wherein said parts may be joined to each other in a simple and inexpensive manner in assembling the cabinet, resulting in low cost of manufacture. 55 Welding of visible parts which requires expensive metal finishing is avoided.

The breaker strips may be very quickly mounted, after the inner and outer casings have been assembled. They engage the adjacent edges of 60 the liner 12 throughout the full lengths of these edges; so that the door closing thrust is evenly distributed to the liner, thereby reducing the danger of cracking the porcelain enamel on the liner.

While I have shown my invention in but one form, it will be obvious to those skilled in the art that it is not so limited, but is susceptible of various changes and modifications without departing from the spirit thereof, and I desire, 70 therefore, that only such limitations shall be placed thereupon as are specifically set forth in the appended claims.

What I claim is:

1. In a cabinet for refrigerators and the like,

the combination of inner and outer sheet metal wall members and a breaker strip connecting adjacent edge portions of said wall members, said breaker strip having a groove receiving the edge portion of one wall member and having a spring means biasing said breaker strip longitudinally of its cross section against said edge portion and transversely against the edge portion of the other wall member.

2. In a cabinet for refrigerators and the like, the combination of inner and outer casings disposed in spaced relation and having a door opening and edge portions at the door opening extending toward each other, a breaker strip extending between said edge portions, said breaker strip having a groove at one edge for engaging one of said edge portions, means for positioning the other edge of the strip against the other edge portion, said means permitting the breaker strip to be moved longitudinally of its cross section for engaging or disengaging said groove and first edge portion, and means for retaining said grooved edge in engagement with the first edge portion.

3. In a cabinet for refrigerators and the like, the combination of inner and outer casings disposed in spaced relation and having a door opening and edge portions at the door opening extending toward each other, a breaker strip extending between said edge portions, said breaker strip having a groove at one edge for engaging one of said edge portions, means for biasing the other edge of the strip against the outer edge portion, said means permitting the breaker strip to be moved longitudinally of its cross section for engaging or disengaging said groove and first edge portion, and means for biasing said grooved edge into engagement with the first edge portion.

4. A double-wall heat-insulated cabinet having a door opening in its front side comprising a liner having walls extending forwardly, an outer casing having a front wall marginal portion and a flange at the edge of the door opening extending toward the forward edge portion of the adjacent wall of the liner, a breaker strip connecting said flange and said edge portion, said breaker strip having a groove at one lateral edge receiving said edge portion, means for biasing said breaker strip longitudinally of its cross section against said edge portion, means for biasing the opposite edge of the breaker strip transversely against said flange, and a door for the cabinet, said other edge of the breaker strip constituting a stop for the door.

5. A double-wall cabinet for refrigerators and

the like having a door opening in its front side and comprising inner and outer casings arranged in spaced relation, the outer casing including a front wall portion having an inwardly extending flange at the door opening, said inner casing having an edge portion adjacent said flange and extending toward said flange, a breaker strip for the door opening having a groove in one edge in which said edge portion is received, the other edge of the breaker strip being disposed on the outer side of said flange and in overlapping relation thereto, a spring member on the inner side of the breaker strip for biasing said other edge transversely against said flange, and a second spring member attached on the inner side of the breaker strip and engaging the inner side of said front wall portion for biasing the breaker strip longitudinally of its cross section into engagement with said edge portion.

6. A cabinet as defined in claim 5, further including a door in said door opening, and wherein the breaker strip constitutes a stop for the door.

7. In a cabinet for refrigerators and the like, the combination of inner and outer sheet metal wall members and a breaker strip connecting adjacent end portions of said wall members, said breaker strip having a surface abutting the end portion of one wall member and having spring means biasing said breaker strip longitudinally of its cross section against said end portion and transversely against the end portion of the other wall member.

8. In a cabinet for refrigerators having a door opening, the combination of inner and outer wall members having a space between them peripherally of the door opening, a breaker strip bridging the spaced apart wall members, means associated with the breaker strip for preventing one edge thereof on one side of said space for moving longitudinally of the cross section of the breaker strip in one direction as well as transversely of its cross section, but permitting movement of the breaker strip longitudinally of its cross section in the other direction, the other edge of the breaker strip freely engaging said cabinet on the other side of said space, and resilient means operatively related to a fixed portion of the cabinet for urging the breaker strip longitudinally of its cross section in said one direction to retain said one edge of the breaker strip in position on said cabinet and transversely of its cross section to retain said other edge of the breaker strip in engagement with the cabinet.

GREGG F. FORSTHOEFEL. 55
